UNITED STATES PATENT OFFICE.

PRICE H. McNEILL, OF OLYMPIA, WASHINGTON.

AUTOMOBILE LAMP.

Application filed September 4, 1924. Serial No. 735,872.

To all whom it may concern:

Be it known that I, PRICE H. McNEILL, a citizen of the United States, and a resident of Olympia, county of Thurston, and State 5 of Washington, have invented a new and useful Automobile Lamp, of which the following is a specification.

The objects of my invention are to provide an automobile lamp, having means whereby the light bulb may be replaced 10 without removing the lens.

A further object is to provide means whereby the usual lamp socket may be used.

I attain these objects by the mechanism 15 illustrated in the accompanying drawing in which:

Fig. 1, is a side elevation of the lamp with a portion of the body broken away.

Fig. 2, is a longitudinal sectional view 20 of the removable portion of the lamp showing the usual lamp socket in place.

Fig. 3 is an end view of the removable portion of the lamp.

Figs. 4, and 5, are end and side views 25 respectively of the spring locking means.

In the drawings, reference numeral, 1, designates a lamp body having a reduced portion, internally screw threaded and adapted to receive the screw threaded 30 tubular plug 3.

To prevent the plug 3, from being loosened by vibration I employ the locking device shown in Figs. 4 and 5, which is substantially a helical spring 4, adapted to 35 movably fit the periphery of the reduced portion 2, of the lamp body as shown in Fig. 1.

The ends 5 and 6, of the spring 4, are 40 formed parallel to the axis of the spring and are adapted to fit an aperture 7, formed in the tubular plug 3, and in aperture 8, formed in the lamp body 1.

I prefer to form the lamp socket and the terminal socket integral with the tubular 45 plug 3. I therefore provide oppositely extending members 9 and 10, of plug 3, adapted to receive the lamp bulb 14, and the terminal plug 17, as shown in Fig. 1. The member 9, is provided with a slot 11, adapted to receive the pin 15, made integral with 50 the terminal plug 17.

The tubular plug 3, may be provided with an aperture adapted to receive any lamp socket as desired. See Fig. 2.

55 When it is desired to remove the lamp

bulb 14, the end 5, of spring 4, is forced longitudinally out of the aperture 7, of the tubular plug 3, and the plug is unscrewed from the lamp body. The lamp bulb is then removed from the socket in the usual manner. When plug 3, is replaced in the lamp the end 5, of the spring 4, is made to enter the nearest aperture in the tubular plug 3 which will hold said plug in secure position.

The bracket 18, is provided with an aperture 19, adapted to receive a through going bolt or the like by which the lamp is secured to the automobile. The terminal wire 65 is shown at 20.

Having fully described my invention what I desire to secure by Letters Patent is:

1. In an automobile lamp, an aperture 75 formed in the body of the lamp, and externally screw threaded plug adapted to engage internal screw threads formed in the said aperture and adapted to receive an electric light bulb, a flange formed on one end of the said plug having slots formed in the periphery of said flange, a helical spring, 80 having one end adapted to engage the slots formed in the periphery of said flange, the opposite end of said spring adapted to engage an aperture formed in the lamp body thereby securely locking said plug in position, substantially as shown and described.

2. In an automobile lamp, an internally screw threaded aperture formed in the body of the lamp, a cylindrical plug, having external threads adapted to engage the threads 90 in said aperture, oppositely disposed members projecting longitudinally from said plug one of said members being adapted to receive an electric light bulb, and the opposite member to receive a terminal plug, 95 a flange formed on the periphery of and adjacent to the threaded portion of said plug, slots formed in the periphery of said flange, a helical spring having one end adapted to engage the slots formed in the 100 periphery of said flange, the opposite end of said spring adapted to engage an aperture formed in the body of the lamp thereby securely locking said plug in position substantially as shown and described.

PRICE H. McNEILL.
